CLAIM

The ornamental design for a foldable kneeling pad, as shown and described.

DESCRIPTION

FIG. 1 is a perspective view of a foldable kneeling pad, showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The straight-line surface shading and stippling in the Figures show contour and not surface ornamentation.
